UNITED STATES PATENT OFFICE.

ALBERT GEORG KOECHLIN, OF STEINEN, GERMANY, ASSIGNEE, BY MESNE ASSIGNMENTS, TO DRAPER COMPANY, OF HOPEDALE, MASSACHUSETTS, A CORPORATION OF MAINE.

CURRENT-DISTRIBUTER FOR POWER-LOOMS HAVING ELECTRICAL STOPPING AND SIGNALING DEVICES.

1,082,429.

Specification of Letters Patent. Patented Dec. 23, 1913.

Application filed July 22, 1911. Serial No. 639,939.

To all whom it may concern:

Be it known that I, ALBERT GEORG KOECHLIN, a citizen of the Republic of Switzerland, residing at Steinen, in the Grand Duchy of Baden, Germany, have invented certain new and useful Improvements in Current-Distributors for Power-Looms Having Electrical Stopping and Signaling Devices, of which the following is a specification.

This invention relates to power looms fitted with devices whereby in certain cases such as for instance the breakage of a warp or a weft thread, the completion of a piece 15 length of fabric, the completion of a certain number of spool changes during a determined period of time, and the like, the loom is stopped automatically by electrical means and a signal is given showing that 20 the loom has been stopped. These devices act by closing an electric circuit so soon as one of the aforesaid cases occurs, whereupon an electric current actuates mechanism which moves the knocking off lever out of 25 its normal retaining catch so that it can snap back into its stopping position. This back movement of this lever is utilized for inserting an electric lamp in circuit which gives the aforesaid signal to the attendant 30 and at night time lights up the loom until the latter is started again. Hitherto a separate switch connected by separate leads to the source of current has had to be provided for each device of this kind, so 35 that the loom installation becomes very complicated and difficult to overlook in cases where a number of such devices are employed in one loom.

Now the present invention has for its object to provide simplified apparatus of this kind in which all the stopping and signaling devices are connected to a common current distributor supplied with current from the source of electricity.

One form of distributor according to this invention is illustrated by way of example in the accompanying drawings in which:

Figure 1 is a section on the line A—B of Fig. 2; Fig. 2 is a section on the line C—D of Fig. 4; Fig. 3 is a front elevation of the distributor; Fig. 4 is a plan of the distributor, without the cover, the loom being stopped. Fig. 5 is a similar plan of the dis-

tributer when the loom is working. Fig. 6 is a similar plan of the distributor when the 55 loom is stopped for examination and repairs. Fig. 7 is a side elevation of the distributor fitted to the loom part of which is shown in section, and Fig. 8 is a plan thereto.

⁶⁰ a is a closed box containing a pin b which is mounted slidably in bearings and carries on it a body c of insulating material of which the middle portion is encircled by a metal sleeve d. The current supplied from one pole of a dynamo or storage battery to a terminal e is led thence by means of a contact spring f to the metal sleeve d. A second contact spring g connects this sleeve through a safety fuse h to a terminal i whence separate leads are led to the various stopping devices. For instance a lead k is led to the warp stop motion; a lead l is led to the weft stop motion, a lead m is led to the piece length measuring off device, and a lead n is led to the stopping device which acts when a certain number of spool changes have been made in succession during a short space of time, and so on. A third contact spring o connects the metal sleeve d through a safety fuse p to a terminal q from which a lead r is led to a glow lamp mounted on the loom. The other pole of the dynamo or storage battery is preferably connected directly to the iron loom framing which serves as a conductor so that no special return leads from the various devices are required. Outside the box there is provided a latch s adapted to be turned into notches t, u of the pin b which has a tendency to be shifted to the left by a spring v.

The box a is mounted at a point of the breast beam w of the loom where the knocking off lever x or a stop y adjustably fixed thereon, can strike the pin b and move it to the right when the lever is moved into the position in which it stops the loom. By this movement the pin b is forced in opposition to the pressure of the spring v into the position shown in Fig. 4 in which all the contact springs are in contact with the metal sleeve d. If this position is to be maintained even after the loom has been restarted, the latch s is turned into the notch t. Otherwise the pin b and the body c are moved by the spring v into the position

shown in Fig. 5, in which the insulating portion of the body *c* is in contact with the contact spring *o* and consequently the glow lamp is cut out of circuit. The contact spring *g* however remains also in this position in contact with the metal sleeve *d* and is therefore ready to supply current to any lead that may be included in circuit.

When it is desired to examine the loom for any reason while it is working or when it is stopped, without desiring to bring the various stopping devices into operation, but while keeping the loom illuminated, then the pin *b* is moved by hand to the right until the latch *s* can be turned into the notch *u* whereby the body *c* is held in the position shown in Fig. 6. In this position the contact spring *g* is in contact with the insulating portion of the body *c*, so that the leads leading to the stopping devices are cut out of circuit, but the lead *r* leading to the glow lamp remains in circuit. Since the safety fuses *h* and *p* will melt as soon as any short circuiting takes place, all risk of danger in the working of the loom is excluded.

The intervening connections between each of the leads *k*, *l*, *m*, and *n*, and the knocking-off lever or shipper handle, and the connections between said lever and the loom clutch or belt shifter are not shown, because well known in the art and constituting in themselves no part of the present invention. It is common in electric stop motions to provide a magnet and electric circuit connections which are rendered operative when the contingency happens for which the stop motion is provided, and to associate the magnet with the knocking-off lever or shipper handle in such manner that the shipper handle is unlatched when the magnet is energized. Such electric stop motions are disclosed in the United States Letters Patent of Chace, No. 633,976, September 26, 1899, and of Coldwell and Gildard, No. 11,923, re-issued July 30, 1901, both of which describe warp stop motions, and in my British Patent No. 26,575, November 16, 1909, which describes a stop motion for stopping the loom in case the weft-replenishing mechanism acts too frequently. Appropriate connections between the shipper handle and the belt shifter are shown in United States Letters Patent of Northrop, No. 593,070, November 2, 1897. Accordingly, the shipper handle *w*, here illustrated is representative of the well-known mechanical features of the stop motion, and the leads *k*, *l*, *m*, and *n*, are representative of the well-known electrical features of the stop motion. The stopping contact *g*, is a part of the stopping circuit and appertains to the electric stopping features, and the signaling contact *o*, is a part of the signaling circuit and appertains to the signaling features. The knocking-off lever is the representative part of

the stopping mechanism which directly acts when the loom stops upon the movable member *b*, of the current distributor.

Having now described my invention what I claim as new and desire to secure by Letters Patent is:—

1. In a loom having electrical stopping and signaling devices and a knocking-off lever, a current distributor for conducting the electric current to the electrical features of said stopping and signaling devices having, in combination, a longitudinally slideable pin in the path of the knocking-off lever, an insulating body thereon, a metal sleeve at the middle of said insulating body, a terminal for the electric current, a contact spring on said terminal adapted to connect it with said sleeve, a contact spring appertaining to the electrical stopping devices and normally in contact with said sleeve, a contact spring in circuit with the electric signal and normally contacting with the insulating body, a spring pressing said pin toward the knocking-off lever into its normal position, the co-action of the parts being such that when the knocking-off lever of the loom is moved from the working position to the inoperative position, said pin is slid against the action of said spring into a position in which both of said contact springs bear upon said sleeve.

2. In a loom having electrical stopping and signaling devices, stopping mechanism, a current distributor for conducting the electric current to the electrical features of said stopping and signaling devices having, in combination, a longitudinally slideable pin, an insulating body thereon, a metal sleeve at the middle portion of said insulating body, a circuit terminal in contact with said sleeve, a contact spring appertaining to the electrical stopping devices and normally in contact with said sleeve, a contact spring in circuit with the electric signal and normally contacting with the insulating body, a spring pressing said pin into its normal position, the co-action of the parts being such that when the loom stops, said pin is slid against the action of said spring by a part of the stopping mechanism into a position in which both said contact springs bear upon said sleeve.

3. In a loom having electrical stopping and signaling devices and stopping mechanism, a current distributor for conducting the electric current to the electrical features of said stopping and signaling devices having, in combination, a longitudinally slideable pin having an insulating body and a metal section, a circuit terminal in contact with said section, a contact spring appertaining to the electrical stopping devices and normally in contact with said section, a contact spring in circuit with the electric signal and normally contacting with the insulating body, a spring pressing said pin into

its normal position, the coaction of the parts being such that when the loom stops said pin is slid against the action of said spring by a part of the stopping mechanism into a 5 position in which said signaling contact spring bears upon said section.

4. A current distributor for looms having electric stopping and signal devices comprising, in combination, a movable member 10 having an electro-conductive section, a circuit terminal in contact with said section, two electric contacts coöperating with said section, one of said contacts appertaining to the stopping devices and the other to the signaling devices, said movable member having three positions, in the first of which the stopping contact touches said conductive section but the signaling contact does not, in the second both contacts touch said conductive section, and in the third the signaling contact touches said section but the stopping contact does not, a spring for moving said member in one direction, the knocking-off lever of the loom which moves said member 15 in the opposite direction when the loom stops, and means for locking the movable member in its second and third positions, said means including two notches in the movable member and a coöperating pivoted 20 latch.

5. A current distributor for looms having electric stopping and signal devices comprising, in combination, a movable member having an electro-conductive section, a circuit 25 terminal in contact with said section, two electric contacts coöperating with said section, one of said contacts appertaining to the stopping devices and the other to the signaling devices, said movable member having three positions, in the first of which the stopping contact touches said conductive section but the signaling contact does not, in the second both contacts touch said conductive section, and in the third the signaling 30 contact touches said section but the stopping contact does not, a spring for moving said member in one direction, the knocking-off lever of the loom which moves said member in the opposite direction when the loom stops, and means for locking the movable member in its second and third positions.

6. A current distributor for looms having electric stopping and signal devices comprising, in combination, a movable member having an electro-conductive section, a circuit 35 terminal in contact with said section, two electric contacts coöperating with said section, one of said contacts appertaining to the stopping devices and the other to the signaling devices, said movable member having three positions, in the first of which the stopping contact touches said conductive section but the signaling contact does not, in the second both contacts touch said conductive section, and in the third the signaling 40 contact touches said section but the stopping contact does not, a spring for moving said member in one direction, the knocking-off lever of the loom which moves said member in the opposite direction when the loom stops, and means for locking the movable member in its second and third positions.

7. A current distributor for looms having electric stopping and signal devices comprising, in combination, a movable member 45 having an electro-conductive section, a circuit terminal in contact with said section, two electric contacts coöperating with said section, one of said contacts appertaining to the stopping devices and the other to the signaling devices, said movable member having two positions, in the first of which the stopping contact touches said conductive section but the signaling contact does not, and in the second the signaling contact touches said section but the stopping contact does not, a spring for moving said member in one direction, the knocking-off lever of the loom which moves said member in the opposite direction when the loom stops, and means for locking the movable member in its third position.

7. A current distributor for looms having electric stopping and signal devices comprising, in combination, a movable member 50 having an electro-conductive section, a circuit terminal in contact with said section, two electric contacts coöperating with said section, one of said contacts appertaining to the stopping devices and the other to the signaling devices, said movable member having two positions, in the first of which the stopping contact touches said conductive section but the signaling contact does not, and in the second the signaling contact touches said section but the stopping contact does not, a spring for moving said member in one direction, the knocking-off lever of the loom which moves said member in the opposite direction when the loom stops, and means for locking the movable member in its second position.

8. A current distributor for looms having electric stopping and signal devices comprising, in combination, a movable member having an electro-conductive section, a circuit 55 terminal in contact with said section, two electric contacts coöperating with said section, one of said contacts appertaining to the stopping devices and the other to the signaling devices, said movable member having three positions, in the first of which the stopping contact touches said conductive section but the signaling contact does not, in the second both contacts touch said conductive section, and in the third the signaling contact touches the contact but the stopping contact does not, and a loom-stopping mechanism coöperating with said movable member.

9. A current distributor for looms having electric stopping and signal devices comprising, in combination, a movable member having an electro-conductive section, a circuit terminal in contact with said section, two electric contacts coöperating with said section, one of said contacts appertaining to the stopping devices and the other to the signaling devices, said movable member having two positions, in the first of which the stopping contact touches said conductive section but the signaling contact does not, and in the second the signaling contact touches the contact but the stopping contact does not, and a loom-stopping mechanism coöperating with said movable member.

10. In a loom having electrical signaling devices and stopping mechanism, a current distributor for conducting the electric current to the electrical parts of said signaling devices having, in combination, a movable 115

member in the path of a movable part of the
stopping mechanism and having an electro-
conductive section, a circuit terminal in
contact with said section, and a signaling
5 contact appertaining to the signaling de-
vices and normally out of touch with said
conductive section but which touches said
section when said member is moved as the
result of the stoppage of the loom, and a

loom-stopping mechanism coöperating with 10
said movable member.

In testimony whereof I have signed my
name to this specification in the presence of
two subscribing witnesses.

ALBERT GEORG KOECHLIN.
